CLAIM

We claim the ornamental design for an interleave with cheese, as shown and described.

DESCRIPTION

FIG. 1 is a top perspective view of an interleave with cheese. FIG. 2 is a top view of the interleave with cheese shown in FIG. 1.

FIG. 3 is a bottom view of the interleave with cheese shown in FIG. 1.

FIG. 4 is a right side view of the interleave with cheese shown in FIG. 1.

FIG. 5 is a left side view of the interleave with cheese shown in FIG. 1.

FIG. 6 is a front view of the interleave with cheese shown in FIG. 1.

FIG. 7 is a rear view of the interleave with cheese shown in FIG. 1.

FIG. 8 is a cross-section view of the interleave with cheese taken through line 8-8 in FIG. 2.

FIG. 9 is a top perspective view of an interleave with cheese.

FIG. 10 is a top view of the interleave with cheese shown in FIG. 9.

FIG. 11 is a bottom view of the interleave with cheese shown in FIG. 9.

FIG. 12 is a right side view of the interleave with cheese shown in FIG. 9.

FIG. 13 is a left side view of the interleave with cheese shown in FIG. 9.

FIG. 14 is a front view of the interleave with cheese shown in FIG. 9.

FIG. 15 is a rear view of the interleave with cheese shown in FIG. 9; and,

FIG. 16 is a cross-section view of the interleave with cheese taken through line 16-16 in FIG. 10.

The broken lines having equal segments represent portions of the article that form no part of the claimed design. The broken lines having unequal length segments illustrate the boundaries between claimed and unclaimed portions of the design and form no part of the claimed design.

In FIGS. 1-16, stippling and straight-line surface shading represent contrast in materials, and the stippling represents the appearance of cheese as indicated by the use of the conventional graphic drawing symbol for cheese in the cross-section of FIGS. 8 and 16.
